(57) **CLAIM**

I claim the ornamental design for a saddle fitting for ultrasonic sensor module, as shown and described.

DESCRIPTION

FIG. 1 is a front perspective view of saddle fitting for an ultrasonic sensor module showing my new design;

FIG. 2 is a left elevation view thereof;

FIG. 3 is a right elevation view thereof;

FIG. 4 is a front elevation view thereof;

FIG. 5 is a rear elevation view thereof;

FIG. 6 is a top plan view thereof; and,

FIG. 7 is a bottom plan view thereof.

Broken lines and the area within the broken lines are for illustrative purposes only and form no part of the claimed design.
